237,498

DENTAL FLOSS DISPENSER

William E. Bennington, 5 Filmore Drive,
Sarasota, Fla. 33581

Filed June 7, 1973, Ser. No. 367,953

Term of patent 14 years

Int. Cl. D24—99

U.S. Cl. D24—1 D

FIG. 1

FIG. 2

FIG. 3

FIG. 4

FIG. 1 is a front end perspective view of a dental floss dispenser embodying my new design showing one side thereof;

FIG. 2 is a back end perspective view of the dental floss dispenser shown in FIG. 1 showing the opposite side;

FIG. 3 is a front end perspective view of a second embodiment of a dental floss dispenser embodying my design showing one side thereof;

FIG. 4 is a rear end perspective view of the dental floss dispenser shown in FIG. 3 showing the opposite side thereof;

I claim:

The ornamental design for a dental floss dispenser, as shown and described.
